CLAIM

I claim the ornamental design for cartridge packaging, as
shown and described.

DESCRIPTION

FIG. 1 is a front, left, top perspective view of the cartridge
packaging according to an embodiment of the invention.
FIG. 2 is a front view of the cartridge packaging of FIG. 1,
showing a front panel.

FIG. 3 is a left side view of the cartridge packaging of FIG.
1.

FIG. 4 is a rear view of the cartridge packaging of FIG. 1.
FIG. 5 is a right side view of the cartridge packaging of FIG.
1.

FIG. 6 is a top plan view of the cartridge packaging of FIG.
1; and,

FIG. 7 is a bottom view of the cartridge packaging of FIG.
1.

The cartridge packaging includes cartridges which are view-
able through transparent material of the front panel. Bullet
portions of the cartridges are shown with stippling and
represent contrasting colors. Broken lines shown in the
drawings are for illustrative purposes and form no part of the
claimed design.
